UNITED STATES PATENT OFFICE.

MARRICK C. BRACKETT, OF HOLLAND, MASSACHUSETTS, ASSIGNOR TO THE STANDARD OPTICAL COMPANY, (LIMITED,) OF GENEVA, NEW YORK.

EYEGLASS.

SPECIFICATION forming part of Letters Patent No. 363,201, dated May 17, 1887.

Application filed November 11, 1886. Serial No. 218,549. (No model.)

To all whom it may concern:

Be it known that I, MARRICK C. BRACKETT, of Holland, in the county of Hampden, in the State of Massachusetts, have invented new and 5 useful Improvements in Eyeglasses, of which the following, taken in connection with the accompanying drawings, is a full, clear, and exact description.

This invention consists, first, in forming the 10 eyeglass-frame and its handle of a continuous piece of wire, thereby permanently connecting said parts without the use of solder; secondly, in forming the eyeglass-frame and nose-guard support or guide of a continuous 15 piece of wire, and thus simplifying the construction and maintaining the connection of said parts intact; thirdly, in a novel connection of the nose-guard and bow to the eyeglass-frame constructed as aforesaid; fourthly, 20 in improved means for securing the cork fac- ing to the nose-guard; and the invention also consists in several other improvements in the construction and combination of parts, as hereinafter described, and specifically set forth in 25 the claims.

In the annexed drawings, Figure 1 is a front view of a set of eyeglasses embodying my improvements. Fig. 2 is a sectional view illustrating the connection of the nose-guard and 30 bow to the eyeglass-frame. Fig. 3 is a trans- verse section on line $\alpha\alpha$, Fig. 1. Fig. 4 is a detached view of the catch or stud-pin by which the eyeglasses are held in their folded position. Fig. 5 is a detached isometric view 35 of the nose-guard; and Fig. 6 is a detached isometric view of the cap or clamp, by means of which the nose-guard and bow are connected to the eyeglass-frame.

Similar letters of reference indicate cor- 40 responding parts.

A represents the eyeglass-frame; B, the handle projecting from said frame; C, the arm by which the elastic nose-guard D is guided and yieldingly supported, and I is the bow 45 which connects the two eyeglasses.

The eyeglass-frame A, with its handle B and the nose-guard guide C, I form of a continuous piece of wire, which may be polished while drawing it from the reel in the operation of 50 forming the aforesaid parts. In the latter operation I bend the wire around a form corresponding to the outline of the eyeglass by taking hold of one end of the wire by a pair

of pinchers, and, while holding said end against the aforesaid form, drawing the wire part way 55 around the form to the point where the handle B is usually attached. This handle I form by bending the aforesaid wire into a laterally-projecting loop. From thence I draw the wire around the remainder of the form to a point 60 in proximity to the place of beginning. Here I bend the wire into another laterally-projecting small loop, a, into which projects the end 65 of the wire held by the pinchers, as aforesaid. From said loop I extend the wire downward and terminate it with a short bend, b, toward 70 the eyeglass, and free from the eyeglass-frame, so as to render said extension elastic. This downwardly-extended end portion of the wire constitutes the guide or supporting-arm C for 75 the lower or vibrating end of the nose-guard D. The wire is clamped around the eyeglass by means of the stud-pin e, which is formed at its attaching end with prongs e' e', and se- 80 cured to the wire at the juncture of the han- 75 dle B with the frame A by introducing the central prong, e', between the portions of the wire forming the loop B and clinching the other prongs, e' e, around the wire, as illus- 80 trated in Fig. 3 of the drawings.

Over the small loop a, I place a cap, d, and by means of a pin, f, passing through the cap at the juncture of the loop a with the frame A, the wire is clamped around the eyeglass and the cap secured to the loop. The nose- 85 guard D, I form of a flat spring-metal bar, the upper end of which I insert in the cap d from the bottom through the top thereof, and bend the protruding upper end over from the eye- 90 glass sufficiently to confine said nose-guard in the cap. It is clamped between the edge of the loop a and adjacent flanges v v on the cap, together with the bow I, which latter is com- 95 posed of a separate piece, and has its end in- 95 serted in the cap and between the inclosed portion of the nose-guard and loop a, as illus- 95 trated in Fig. 2 of the drawings.

The lower end of the nose-guard D, I bend toward the eyeglass, and provide the same with a slot, t, into which the lower end of the arm C projects. The nose-guard is thus connected with the arm C in such a manner as to allow the former to yield to the pressure when sup- 100 porting the eyeglasses on the nose, the arm C serving to guide the nose-guard.

To the face of the nose-guard I apply a cork

strip, *s*, for the protection of the nose of the person wearing the glasses. This cork strip I secure in position on the nose-guard by providing the upper and lower ends of the latter with perforations *u u*, and winding around the cork strip and nose-guard a thin pliable wire, and passing the ends thereof through the perforations *u u* and tying them on the nose-guard. I draw the wire tightly across the cork, so as to partly embed the wire therein, and thus obviate the danger of injuring the nose of the wearer.

Having described my invention, what I claim as new, and desire to secure by Letters Patent, 15 is—

1. The combination of an eyeglass-frame and its handle, composed of a continuous piece of wire encircling the lens and bent into a loop intermediate its length and a clamp embracing the wire at the junction of the aforesaid loop with the frame, substantially as set forth.

2. The combination of an eyeglass-frame and its handle, composed of a continuous piece of wire encircling the lens and bent into a loop intermediate its length, and a stud-pin having at its attaching end prongs clinched around the wire at the junction of the aforesaid loop with the frame, substantially as described and shown.

3. The eyeglass-frame and nose-guard guide, composed of a continuous piece of wire, as set forth.

4. The eyeglass-frame and nose-guard guide, composed of a continuous piece of wire encircling the lens, and having one of its extremities extending past the other extremity, and adapted to support the nose-guard, as set forth.

5. The eyeglass-frame and nose-guard guide, composed of a continuous piece of wire encircling the lens, and having one of its extremities extending past the other extremity and terminated with an elastic arm standing clear from the frame, substantially as described and shown.

6. The eyeglass-frame, its handle, and nose-guard guide, composed of a continuous piece of wire encircling the lens and bent intermediate its length into a lateral projection to serve as a handle, and having one extremity extending past the other extremity and terminating with an elastic arm standing clear from the frame, substantially as set forth and shown.

7. The combination of the eyeglass-frame and nose-guard guide, composed of a continuous piece of wire encircling the lens and bent into a laterally-projecting loop, one end of the said wire terminating at the loop and the other extremity of the wire extending from the loop and terminating with an elastic arm standing clear from the frame, and a clamp embracing said loop, substantially as set forth.

8. The combination of the eyeglass-frame and nose-guard guide, composed of a continuous piece of wire encircling the lens and bent into a laterally-projecting loop, one end of the

said wire terminating in said loop and the other extremity extending from the loop and terminating with an elastic arm, a clamp embracing said loop, and the nose-guard secured at one end to the said clamp, and having its free end connected with the free end of the aforesaid elastic arm of the wire, substantially as described and shown. 7c

9. The combination of the eyeglass-frame and nose-guard guide, composed of a continuous piece of wire encircling the lens and bent into a laterally-projecting loop, one end of said wire terminating in said loop and the other end extending from the loop and terminating with an elastic arm standing clear 80 from the frame, a clamp embracing said loop, the nose-guard secured at one end in the clamp, and having its free end connected with the free end of the aforesaid elastic arm of the wire, and the bow consisting of a separate 85 piece secured at its end in the aforesaid clamp, substantially as described and shown.

10. The combination of the eyeglass-frame and nose-guard guide, composed of a continuous piece of wire encircling the lens and bent into a laterally-projecting loop, the end of said wire terminating in the loop and the other end extending downward from the loops, a cap inclosing the loop, a pin passing through the cap at the side of the neck of the loop, the 95 nose-guard having its upper end inserted in the cap and its lower end connected with the downward extension of the aforesaid wire, and the bow composed of a separate piece, having its end inserted between the upper end of the 100 nose-guard and the loop with the inclosing-cap, substantially as described and shown.

11. The nose-guard composed of a flat metallic bar and a cork strip secured to the face of said bar by a wire wound around the bar 105 and cork strip, substantially as set forth.

12. The nose-guard composed of a flat metallic bar provided with perforations and a cork strip secured to the face of said bar by a wire wound around the bar and cork strip, and passing through the perforations of the bar and fastened thereto, substantially as described 110 and shown.

13. The combination, with an eyeglass, of the arm *C* and the nose-guard *D*, the latter composed of a flat spring-metal bar secured at its upper end to the eyeglass, and having its lower end bent toward the eyeglass and provided with a slot for the reception of the lower end of the arm *C*, substantially as described 120 and shown.

In testimony whereof I have hereunto signed my name and affixed my seal, in the presence of two attesting witnesses, at Brimfield, in the county of Hampden, in the State of Massachusetts, this 8th day of November, 1886.
